UNITED STATES PATENT OFFICE

2,664,135

SPARK PLUG GAPPING MACHINE

Lewis M. Oden, Sr., Norfolk, Va.

Application November 21, 1950, Serial No. 196,919

5 Claims. (Cl. 153—48)

(Granted under Title 35, U. S. Code (1952),
sec. 266)

1

The present invention relates generally to tools and specifically to spark plug gap setting tools.

This application is a continuation in part of my copending application Serial No. 552,113, filed August 31, 1944, now Patent No. 2,481,530, granted September 13, 1949, and has for its principal object the provision of an improved tool by which the gap between the central and the shell electrodes of a spark plug can be gauged simultaneously with the bending of the grounded electrodes to the position whereby the gap formed between the electrodes is that found to result in the optimum efficiency of the internal combustion engine in which the spark plug is used.

Another object of the invention is to provide an improved tool for use on spark plugs of the type used in aviation engines wherein the forming of the electrode surfaces of the grounded or shell electrodes and the final adjustment of the gap between the electrodes is accomplished in a single operation of the tool without the imposition of any bending moment to the central electrode of the plug.

Another object of the invention is to provide an improved tool wherein two or more grounded or shell electrodes of a spark plug can be simultaneously adjusted with respect to the central or insulated electrode.

A further object of the invention is to provide an improved tool wherein the spark plug is universally mounted to facilitate proper alignment thereof prior to and during the operation of the tool.

Other objects and advantages of the invention will be in part evident to those skilled in the art, and in part pointed out hereinafter in the following description taken in connection with the accompanying drawings wherein there is shown by way of illustration and not limitation preferred embodiments thereof.

Figure 1 is a view showing the invention in side elevation.

Figure 2 is a front elevational view thereof.

Figure 3 is a view in side elevation with parts broken away to better illustrate the operation of the tool.

Figure 4 is a horizontal sectional view taken on the line 4—4 of Figure 3.

Figure 5 is an enlarged detail view, partly broken away on the line 5—5 of Figure 4, to better illustrate the gapping operation of the tool.

Figure 6 is an enlarged sectional view of the feeler gauge chuck assembly.

Figure 7 is a detailed view of the vice block associated with the feeler gauge chuck.

2

Figure 8 is a detail view of one of the chuck jaws.

Figure 9 is a side elevational view with part broken away showing a modified form of the tool and cylinder block.

Figure 10 is a detail front elevational view partly broken away of the cylinder block assembly shown in Figure 9.

Figure 11 is a bottom view of the cylinder block shown in Figure 10, and,

Figure 12 is an enlarged detail sectional view of a modified form of spark plug adapter.

Referring to the drawings in detail, in Figures 1, 2 and 3 the reference character A indicates

15 generally my improved spark plug gapping tool, which comprises a main frame or arbor 10 having spaced upper and lower jaws 11 and 12 respectively and a base 13. Said base 13 is provided with bosses 14 and 15 which are bored to receive bolts 16 by means of which the tool can be fastened to any suitable support.

The upper jaw 11 is provided with two spaced parallel bores 18 and 19. A plunger 20 having rack teeth 21 formed thereon is slidably mounted 25 within the bore 18. A shaft 22 having a pinion 23 formed thereon is journaled in a bore 24 formed in and extending transversely through the upper jaw 11. Pinion teeth 23 engage with the teeth of the rack 21. The shaft 22 is retained within the bore 24 by means of a washer 26 fixed to the end of the shaft 22 by means of a screw 27.

The plunger 20 is provided with a central bore 28 into the lower end of which is slidably mounted a stud 29 formed integral with and extending upwardly from an adapter block 30 having a bore 31 formed therein.

40 A feeler gauge chuck assembly C, similar to the well-known Jacobs chuck used extensively in machine shops is rotatably mounted to the underside of said adapter block by means of stud 32 secured within the bore 31 in said adapter block by means of set screw 33.

The chuck assembly C as shown in Figure 6 comprises a main body portion 34 having a groove 35 formed therein to accommodate a split nut 36. A sleeve 37 having gear teeth 38 formed in the lower end thereof is rotatably mounted over the body portion 34 of said chuck and is fixed in any suitable manner to the split nut 36. The body 34 is further provided with three diverging bores 39, in each of which is slidably mounted a chuck jaw 40. Said chuck jaws 40 are provided with threads 42 adapted to engage the threads of the split nut 36, whereby rotation of said nut will cause the chuck jaws 40 to move upwardly or

downwardly in their respective bores depending on the direction of rotation of said sleeve nut. The chuck jaws 48 are provided with a cutaway portion 44 to form a seat 44a upon which rests the head 45 of a spring-pressed vice block 46. Said vice block 46 is disposed centrally of the body 34 beneath its lower wall 47 and comprises a triangular shaped shank 48 which depends between the flat vertical faces 49 of the chuck jaws 40. The flat faces 50 of the shank are aligned 10 with the vertical faces 49 of the chuck jaws 40, and together provide a simple effective vice between which the feelers 53 are clamped.

A portion of the head 45 of the vice block 46 is thickened 25 as at 45a to cause the one feeler 54 to extend below the lower end of the feelers 53, the purpose of which is to facilitate the insertion of the feelers within the gap between the central and shell electrodes of the spark plug. The blade portion of said feelers is chamfered along its edges to insure against kick-back of the grounded or shell electrodes during gapping operation and is also shaped to conform to the radius of the central electrode of the particular type of spark plug to be gapped.

A coil spring 51 is located within the bore 28 of the plunger 29 and extends between the upper face of the stud 29 and the shoulder 58 of the bore 28 at the point of reduced diameter of the bore. The stud 29 is adjustably held within the bore 28 against the pressure of the spring 57 by means of an elongated bolt 59, the head 60 thereof resting upon the upper surface of the plunger 29 and its lower end 62 threaded into the tapped bore 63 in the stud 29.

It will be noted from the description, and with reference to Figure 3 of the drawings, the operator can accurately adjust the feeler gauge chuck assembly C and consequently the feeler gauges 53 with respect to the lower jaw 12 of the tool to accommodate for spark plugs of varying lengths.

A push-rod 67 adapted to reciprocate within the bore 16 in unison with the plunger 29 is connected thereto by means of yoke 68. One end 45 of said yoke is fitted over the reduced end 69 of the plunger 29 and is held thereon by means of a tapered pin 70. The opposite end thereof is bored and tapped to receive an adjustable bushing 71 having a bore through which the push-rod 67 passes. Said push-rod is adjustably fixed therein by means of set-screws 72.

A guide member 73 having a central bore 74 through which passes the lower end of the push-rod 67 is fitted into the upper end of the bore 19. 55 The end of said push-rod is in turn screw threaded as at 75 into the upper member 76 of a two part coupling 77. The lower member 78 thereof and its upper member 76 are hinged together as at 79. The lower member 78 is in turn connected 60 to the stem 80 of the piston 81 mounted in the fluid pump 82 by means of lost motion connection 83. In the present instance a pin and slot connection is shown, but any well-known type of lost-motion connection can be utilized for the 65 purpose.

A compression spring 84 is provided to hold plunger 29 and the push-rod 67 up in inoperative position and is mounted by having the upper face of the guide member 73 form a seat for the lower 70 end of the spring 84 which as shown surrounds the push-rod 67 and extends upwardly between the upper jaw 11 of the main frame 10 and the underside of the yoke 68. The upper end of the spring seats in a bored washer 61 which bears 75

against the lower end of the adjustable bushing 71. As shown, the spring 84 can be readily adjusted to vary the action of the tool by means of the bushing 71.

The fluid pump 82 comprises a casting 85 having a cylinder 86, a piston 81 reciprocatably mounted within said cylinder, and bonnet 87. The bonnet 87 is screw threaded as at 88 into the casting 85, said bonnet being centrally bored to allow the stem 80 of the piston 81 to pass therethrough. The casting 85 is in turn screw threaded into the tapped bore 89 formed in the ram block 90. Said ram block 90 is secured in place upon the upper surface of the lower jaw 12 of the main frame 10 by means of bolts 91.

As shown in Figure 4, the ram block 90 has formed therein three equi-angularly spaced horizontally disposed bores 92, 93 and 94 into which are fitted pistons 95, 96 and 97, respectively. The pistons 95, 96 and 97 are fitted with gapping rams 98, 99 and 100, respectively the ends of which are machined as at 101 to form electrode shaping dies. Said rams extend inwardly through the bores 102, 103 and 104 into the opening 105 formed in the front portion of the ram block 90.

Springs 106, 107 and 108 are positioned between the inner ends of the bores 92, 93 and 94 and the inner faces of the pistons 95, 96 and 97, and are adapted to retain said pistons and rams in their retracted position until influenced by the fluid pump 82. The bores 93 and 94 are connected to the bore 22 by means of fluid passages 109-110 and 111-112 respectively. The bore 82 is in direct communication with the fluid pump 82. The outer ends of bores 92, 93 and 94 are sealed by means of plugs 113, 114 and 115 respectively, said plugs being bored and tapped to receive adjustable stops 116, 117 and 118 adapted to limit the outward movement of the pistons 95, 96 and 97 after the pressure on said pistons has been released.

As shown in Fig. 3 screws 119 with a "dog" point are threaded in the ram block 90 and are adapted to coat with the slotted portions 120 of the rams 98, 99 and 100 so as to hold in alignment the radii or die ends of rams with respect to the outer electrodes of the spark plug to be gapped. Screws 119 are not used to stop the inward travel of the rams 98, 99 and 100. Stop screw 121 (see Fig. 3) is used to limit the travel of rams 98, 99 and 100 inwardly so that no damage may be done to the chuck jaws of rams when no spark plug is in the machine to catch the travel of the rams.

The lower jaw 12 projects beyond the front of the main frame 10 to provide a bifurcated support 123 containing a spark plug 132 during gapping operation of said tool. Said bifurcation is in alignment with the opening 105 in the ram block 90 and that portion of the underside of said block adjacent the opening 105 is machined to form a recess 124 into which the radial flange 125 of the spark plug adapter 126 loosely fits when the adapter is positioned upon the support 123. In operation the adjustable spark plug adapter 126 abuts the adjustable stop 133 positioned at the root of the bifurcated support 123 when in proper alignment with the feeler gauges 53.

The spark plug adapter 126 comprises an internally threaded body 128, which is provided at its top with the annular flange 125. An adjustable nipple 129 is threaded into the body 128 and is retained therein by means of a jam nut 53.

130. Said nipple 129 is further provided with an extending annular flange 131 upon which rests the shell hex of the spark plug 132. The harness end of the spark plug extends downwardly through the nipple 129 and its electrode end extends upwardly into the opening 105 in the block 90 between the rams 98, 99 and 100 as shown in Figure 5. It is intended that the spark plug 132 fit loosely in the adapter 126 and the adapter fit loosely between the bifurcated support 123 with its annular flange 125 resting upon the ledge 127 of said support so that the spark plug can be easily shifted and aligned with the feelers 53 and the rams 98, 99 and 100 before the gapping operation of said tool is begun.

As shown in Figure 5, the chuck assembly C and the feeler gauges 53 have been moved downwardly into the gapping position with the spark plug 132 mounted in the body 128 with the flange 125 resting upon the ledge 127 of the support 123. The rams 98, 99 and 100 as shown are about to be moved inwardly under the pressure of the pump 82 towards the central insulated electrode of the plug to thereby bend the shell electrodes towards the central electrode to clamp the feeler gauges 53 therebetween.

In ordinary use, a large number of spark plugs of the same make are gapped at one time. If a different lot of another type of plugs is to be gapped, for example, two or four electrode plugs, the ram block 90 can be readily replaced by another type of cylinder block, such as that shown in Figures 9, 10 and 11.

The operation of the tool is as follows: After the spark plug 132 has been placed within its adapter 126 and said adapter positioned in the tool, plunger 20 and the chuck assembly C are lowered by rotating the pinion 23 by means of the operating handle 134 fixed in the bore 135 in the end of the shaft 22. While the chuck assembly C is being lowered the operator may either oscillate the chuck assembly or rotate the spark plug holder in order to start the pilot gauge 54 into the gap between the shell and central electrodes of the spark plug and to cause the remaining feelers to follow therein. The operator must properly align the feelers with the shell electrodes and the electrodes with the rams before proceeding further. After they are aligned, the operator continues to move the feelers downwardly until they have reached their proper depth within the gap and until the stop 136 carried by the adapter block 30 is in contact with the upper surface of the ram block 90 thereby preventing further downward movement of the feeler 53. At this point the pin of the lost motion connection between the piston 81 of the pump 82 has moved into contact with the bottom of its slot and the operator continues to move the plunger 20, yoke 68, and the push-rod 67 downwardly to operate the piston 81 of the pump 82 to force the pistons 95, 96 and 97 by fluid pressure inwardly and cause the rams 98, 99 and 100 to move inwardly and to bend the shell electrodes until the feelers 53 are clamped between the shell and central electrodes. The adjustable stop 137 carried by the yoke 68 contacts the upper surface of the jaw 11 of the main frame 19 when there is no plug in the machine and which prevents further downward movement of the operating handle, and is stopped by the rams against the electrodes, the pressure gauge 121 indicating the pull exerted on the handle.

The construction of the tool allows the spark plug to be shifted into exact proper alignment

with the feelers and permits the rams to exert force on the shell electrodes without imposing bending strain on the center electrode of the spark plug. The feelers are constructed of sufficiently flexible material and so formed as to fit the radius of the center electrode and are so ground that they can be withdrawn from the gaps without disturbing the setting of the gaps.

Since the material of the spark plug electrodes is slightly resilient, the shell electrodes will spring back slightly after the rams are backed away and the feelers are therefore constructed thinner than the desired gap to allow the shell electrodes to be pressed in the distance they will spring back. 10 The withdrawal of the rams and feelers is automatic when the operator raises the handle 134 or allows it to be raised by the action of the spring 84. The rams are assisted in their return to the inoperative position by the action of springs 106, 15 107 and 108 disposed between the ends of the bores 92, 93 and 94 and the inner faces of said pistons on the release of the hydraulic pressure in the tool. The vertical range of movement of the chuck assembly C is less than that of the plunger 20 because of the sliding action of the stud as previously described.

30 The tool may be adjusted by several means to accommodate spark plugs of a wide variety of sizes and makes; the time spent in changing the tool to fit one size of spark plug or another is inconsequential as compared to the time saved by gapping a lot of the same sized plugs at one time.

In order to perform gapping operations on spark plugs having two or four shell electrodes 35 instead of three as has been illustrated, the operator merely substitutes another ram block as shown in Figure 9 for the one shown in Figure 5. This ram block is constructed with two rams opposite each other and the gapping of a four electrode spark plug is done by rotating the spark plug 90 degrees after the first opposing pair of electrodes are gapped. A spark plug having six 40 equally spaced electrodes can similarly be gapped by double ram in three operations and so on.

45 The ram block shown in Figures 9, 10 and 11 is adapted for use in connection with spark plugs having two or more opposing shell electrodes and although the block is shown applied to a modified form of tool, it should be understood that it is also adaptable to that type of tool as shown in Figure 1 of the drawings.

The ram block 300 comprises a main body 301 having a bifurcated front portion 302 forming a recess 303 and a vertical bore 304, said bore is 50 reduced as at 305 to accommodate the threaded end 306 of the pump cylinder 307. The bore 304 is closed at its top by means of a cap plug 308, thereby providing a seal for the reservoir 309 formed by said bore. The bore of the pump cylinder 55 communicates with the reservoir 309 by means of ports 310 formed through the walls of said pump cylinder. The cap plug 308 is centrally bored to permit the passage of the stem 311 of the piston 312 which is in turn mounted in the 60 pump cylinder 307. The block is further provided with two diametrically opposed diverging bores 321 connected to the bore of the pump by means of fluid passages 315 and 316. Pistons 317 are mounted in bores 321 and are provided 65 with rams 319 the ends of which are machined to form electrode forming dies 320. The rams 319 extend inwardly through the bores 321 into the recess 303 formed in the bifurcated front portion of the main body 300. Springs 323 are disposed 70 between the ends of the bores 321 and the inner

face of the pistons 311 and are adapted to hold the pistons and rams in retracted position until influenced by pressure from the pump 311. The outer ends of the bores 321 are sealed by means of plugs 324 which are centrally bored and tapped to receive the adjustable stops 325 adapted to limit the outward movement of the pistons 311. Stops 326 are provided in the front end of the block 309 and are adapted to coact with the slots 327 formed in the rams 319 for the purpose of aligning the radii surfaces of dies on the rams with the outer surface of the outer electrode of the spark plug.

While the piston and the rams shown in Figure 5 are disposed perpendicularly with respect to the vertical axis of the spark plug it should be understood that said pistons and rams could be disposed as shown in Figure 10 of the drawings in order to accommodate spark plugs having three shell electrodes requiring angular adjustment thereof, and similarly the arrangement of the rams and pistons shown in Figure 10 could be modified to accommodate spark plugs requiring the adjustment to be made perpendicularly to the vertical axis of the spark plug.

In Figure 12 is shown the spark plug holder composed of the hollow tubular body 330 with internal threads 331 and threaded plug 332. A steel ball 333 is centered in the conical cavity 334 and is a support for the hollow stem 335 of a spark plug inserted in the holder. The body 339 has an annular shoulder 336 to rest on the bifurcated front portion 362 of the gapping tool illustrated in Figures 9, 10 and 11. The tubular body 330 may be provided with threads (not shown) to fit the spark plug adapter 126 of Figures 1, 2, 3, 4 and 5, or otherwise used with the gapping tool of those figures without departing from the scope and intent of the invention.

The spark plug holder is so constructed as to permit spark plugs being gapped to be pivoted on the steel ball 333 and to float away from the greater force that might be exerted upon either of the electrodes being gapped, and is also adjustable by moving plug 332 to accommodate plugs of varying lengths.

The invention described herein may be manufactured and used by or for the Government of the United States of America for governmental purposes without the payment of any royalties thereon or therefor.

What is claimed is:

1. A gap setting tool for spark plugs having shell and central electrodes comprising a base, a holder for a spark plug adjustably mounted on said base, a reciprocating plunger movably mounted on said base, at least one feeler gauge attached to said plunger, an operating handle geared to said plunger, an electrode bending ram reciprocatingly mounted on said base, hydraulic means mounted on said base for actuating said ram, and a hydraulic piston coacting with said plunger for providing pressure to said hydraulic means.

2. A gap setting tool for spark plugs having shell and central electrodes comprising a base, a holder for a spark plug adjustably mounted on said base, a reciprocating plunger mounted on said base substantially axially with said holder, a feeler gauge mounted on the end of said plunger, a yoke attached to the other end of said plunger, an adjustable stop to limit the travel of said plunger, a cylinder mounted on said yoke, a piston reciprocating in said cylinder, an electrode bending hydraulic ram reciprocatingly mounted in a

chamber attached to said base, hydraulic connections between said cylinder and said chamber, and an operating handle geared to said plunger whereby said feeler gauge is limitedly inserted between the electrodes of the spark plug and said hydraulic ram and bends the shell electrode to form the gauged gap with one stroke of said handle.

3. A gap setting tool for spark plugs having shell and central electrodes comprising a base, a holder for a spark plug adjustably mounted in an opening in said base, a plunger slidably mounted in a channel in said base axially with said holder, at least one feeler gauge mounted in a chuck on one end of said plunger and adapted to be inserted between the electrodes of the spark plug, a yoke attached to the other end of said plunger, an adjustable stop to limit the travel of said plunger, a rack gear cut into the side of said plunger engageable with a spur gear pinionized in said base, an operating handle attached to said spur gear, at least one chamber in said base radial of said opening, a hydraulic ram mounted in said chamber, a die attached to each ram at the inner end adapted to fit the shell electrode, a hydraulic pump operable by said yoke mounted on said base, and connecting means between said pump and said chamber.

4. A gap setting tool for spark plugs having shell and central electrodes comprising a base, a holder for a spark plug adjustably mounted in an opening in said base, said holder having a conical cavity and a ball centered in said cavity adapted to fit the tubular stem of a spark plug, a plug slidably mounted in a channel in said base axially with said holder, at least one feeler gauge mounted in a chuck on one end of said plunger and adapted to be inserted between the electrodes of the spark plug, a yoke attached to the other end of said plunger, an adjustable stop to limit the travel of said plunger, a rack gear cut into the side of said plunger engageable with a spur gear pinionized in said base, an operating handle attached to said spur gear, at least one chamber in said base radial of said opening, a hydraulic ram mounted in said chamber, a die attached to each ram at the inner end adapted to fit the shell electrode, a hydraulic pump operable by said yoke mounted on said base, and connecting means between said pump and said chamber.

5. A gap setting tool for spark plugs having shell and central electrodes comprising means for adjustably mounting said spark plug on a base, feeler means for said spark plug movably mounted on said base and adapted for insertion between the electrodes of said spark plug, ram means movably mounted on said base for bending the electrodes of said spark plug by an amount determined by said feeler means, and means for moving said feeler means and said ram means, said means comprising a movable yoke, means coupling said feeler means to said yoke, hydraulic means, lost motion coupling means, and means connecting said yoke to said ram means through said lost motion coupling means and said hydraulic means.

LEWIS M. ODEN, SR.
